(57) CLAIM

The ornamental design for a card storage box, as shown and described.

DESCRIPTION

FIG. 1 is a front view of a card storage box of the present invention;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a top perspective view thereof; and,

FIG. 8 is a top perspective view of the card storage box, showing the box in another configuration with two side panels open.

The broken lines depict a boundary of the claim and form no part of the claimed design.

1 Claim, 8 Drawing Sheets
